By his Attorney,
Nelson M. Howard

UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING-MACHINE.

1,315,947.

Specification of Letters Patent. Patented Sept. 16, 1919.

Application filed March 7, 1918. Serial No. 221,054.

To all whom it may concern:

Be it known that I, JOHN W. COSGROVE, a citizen of the United States, residing at Medford, in the county of Middlesex and 5 State of Massachusetts, have invented certain Improvements in Cementing-Machines, of which the following description, in connection with the accompanying drawings, is a specification, like reference characters on 10 the drawings indicating like parts in the several figures.

This invention relates to apparatus for cementing sheet material and particularly to that adapted for applying cement along the 15 edges of the material.

An object of the invention is to arrange such an apparatus to operate upon adjacent or intersecting edges of work carrying a row of spaced projections. To attain this object 20 I provide a novel work support having spaces designed to allow the successive passage of the projections in a series or the passage of a plurality of said projections simultaneously. For this purpose I may employ 25 a plurality of supports separated from one another so as to receive readily the row of projections as an edge of the work is operated upon, one of the supports having a space which co-operates with that between 30 the supports to admit therewith two projections when the work is turned to operate on another edge.

Another object of the invention is to insure the application of cement to one face 35 only of the work, avoiding the doubling over of the uncemented side of the material into contact with the cement-applying means. To this end my improved apparatus includes novel fold-preventing means 40 operating with the work adjacent to the applying means. As herein disclosed, this fold-preventing means consists of scraping members contacting with the work, preferably on opposite sides, and, since the doubling 45 of the material is usually caused by its pressure against the gage which determines its position with relation to the applying means, I have shown the scrapers mounted on the work-engaging face of the gage.

50 One embodiment of the invention is illustrated in the accompanying drawing; in which,—

Figure 1 is a perspective view of my improved cementing apparatus;

55 Fig. 2 is a detail in vertical section

through the axes of the applying and supporting rolls;

Fig. 3 is a detail in perspective showing the rear of the work support, and

Fig. 4 is a similar view of the gage with 60 its fold-preventing means.

The general construction of the apparatus is similar to that disclosed in my Patent No. 1,242,925, dated Oct. 16, 1917. This includes a frame 10 at the top of which is 65 mounted a tank 12 delivering, under the control of the valve 16, to a rotatable cement-applying roll 14. Fulcrumed at 18 upon the frame, and extending beneath the applying roll, is a lever 19 forced normally upward by 70 a spring not here shown, since it is arranged similarly to that in the above-mentioned patent. Upon the outer extremity of the lever an arm 20 is pivoted at 22, being held in normal alinement with the lever by a pin 75 24 but when the pin is removed being capable of being swung down to enable the parts carried to be cleaned. At the outer end of the arm is an upwardly extending portion 26, here shown as integral, in which is a 80 bearing for the spindle 28 of a work-supporting roll 30 which is situated below the inner edge of the applying roll 14. Separated from the roll by a space at 32 is a second supporting member 34, appearing as a 85 vertical bar, secured to the side of the arm 20 by a screw 36 and having an upper work-engaging surface 38, which may be curved so that it has the same contour as a portion 90 of the periphery of the roll 30. The screw 36 preferably passes through a vertical slot in the bar, by means of which connection the supporting member 34 may be adjusted toward and from the applying roll 14. This allows the support to better present the work 95 to the applying roll when said work is of different thicknesses across the area to be cemented. The work-engaging surface 38 is slotted at 40, the width of this slot being substantially equal to that of the space 32, 100 each being adapted to permit the passage of a projection carried by the work and being separated from one another by a distance equal to the spacing of the projections. This slot 40 divides the support 34 into two portions 42 and 44, the former being situated below the outer edge of the cement-applying roll while the portion 44 is midway between its companion and the roll 30. If work indicated at W and consisting, for example, 110

of a shoe upper which has such a row of 5 projections as lacing hooks *w* extending along the inner edge, is to be cemented along said edge and its top edge for securing the lining prior to stitching, it may first be introduced between the applying roll 14 and the support, with the row of hooks in alignment with the space 32. As the work is advanced between the support and applying 10 roll, the roll 30 and portions 42 and 44 hold the surface to be cemented into effective contact with the periphery of the applying roll, the space 32 allowing the hooks to pass through without interference, one after another. When the upper is turned to cement 15 across the top, the first of the series of hooks enters the space 32 while the second passes through the slot 40. Here also, interference with the projections is avoided, while practically the entire surface to be cemented is 20 forced uniformly against the applying roll.

To guide work by contact with its edge so that the area cemented may be uniform in width, a gage is provided. This is here 25 illustrated as consisting of a block 46 having an inner reduced portion 48, the faces of which are curved similarly to the peripheries of the applying and supporting rolls so the gage may be brought into close proximity with them. From one side of the 30 lower portion of the block extends an arm by which the gage may be secured to the lever 19, this being by means of a screw 52 passing through a horizontal slot in the arm, allowing the gage to be adjusted to 35 vary the width of the area cemented. It is found that in coating some types of material which are thin and flimsy, contact of the edge of the work with the vertical guiding 40 surface 54 of the gage causes the material to be doubled over, so that the wrong side is presented to the applying roll and the work defaced. To avoid this, fold-preventing means is placed adjacent to the applying 45 roll, it preferably consisting of members 56, 56 mounted upon the surface 54 of the gage for scraping over opposite sides of the work. These members I have shown as 50 of thin resilient material mounted on studs 58, 58 extending through horizontal bores in the block 46, these studs being threaded at the inner side of the block to receive nuts 60 for clamping the members 56 against the face 54. The members 56, 56 converge from 55 the supporting studs toward a point near the reduced extremity of the gage, forming an acute angle with one another. At their adjacent extremities they are bent until they approach at 62 in substantially a straight line, being there approximately at right angles to the surface of the work. Said work is readily introduced into the tapered throat formed by the converging members, which yield from one another to permit this, 60 and drawn between the ends 62 into engage-

ment with the applying roll and support. As it is fed along by the rotation of the applying roll the ends of the members 56 drag over the edge close to the gage, and if the pressure against the surface 54 tends to fold 70 this edge upon itself, this is immediately straightened by the members. Their action in this respect is more effective because of the direct approach of the ends, it being found that if they are inclined throughout 75 their length at the angle of their body portions there is a tendency to catch the fold between them, so that it is pressed down and held rather than removed. With the ends formed as herein described, it is practically 80 impossible for a doubled portion to enter between the members. To provide for the proper coöperation with work of different thicknesses and the tension under which the engaging ends 62 are forced against it by 85 the resilience of the members 56, the angular relation of said members may be changed by loosening the nuts 60, turning the studs to the desired positions and reclamping them.

Having thus described my invention, what 90 I claim as new and desire to secure by Letters Patent of the United States is:

1. In an apparatus for cementing the edges of work along one of which edges is a row of spaced projections, a cement-applying member, and an opposed supporting member, the supporting member having spaces one of which is separated from its edge a distance substantially that by which the row of projections is separated from an 95 edge of the work, thereby allowing the successive passage of said row of projections while the edge of the work beneath them is being cemented, the separation between 100 said spaces corresponding to that between 105 the projections and thus receiving a plurality of projections simultaneously when another edge is being acted upon.

2. In an apparatus for cementing the edges of work along one of which edges is 110 a row of spaced projections, a cement-applying member, and a plurality of supporting members separated by a space to allow the passage of the projections, one of said members being provided with a space for receiving 115 a projection simultaneously with the space between the members.

3. In an apparatus for cementing the edges of work along one of which edges is a row of spaced projections, a cement-applying member, a rotatable work-supporting roll, and a non-rotatable support adjacent to the roll but separated therefrom by a space sufficient to allow the passage of the row of 120 projections, the non-rotatable support having 125 a slot in its work-engaging face.

4. In an apparatus for cementing the edges of work along one of which edges is a row of spaced projections, a cement-applying member, a plurality of supporting mem- 130

- bers separated by a space to allow the passage of the projections, one of said members being provided with a space for receiving a projection simultaneously with the space between the members, and means constructed and arranged to permit the relative height of the supporting members to be varied. 5
5. In an apparatus for cementing the edges of work along one of which edges is a row of spaced projections, a cement-applying member, a rotatable work-supporting roll, and a non-rotatable support adjacent to the roll but separated therefrom by a space sufficient to allow the passage of the row of projections, the non-rotatable support having a slot in its work-engaging face and being adjustable toward and from the applying member. 10
6. In a cementing apparatus, a cement-applying roll, a lever fulcrumed below the roll, a work-supporting roll rotatable upon the lever opposite the applying roll, and a support having a slotted work-engaging face and being fixed to the lever and spaced 15 from the roll. 20
7. In a cementing apparatus, a cement-applying roll, a lever fulcrumed below the roll, a work-supporting roll rotatable upon the lever opposite the edge of the applying roll, and a support fixed to the lever and having two work-engaging portions, one of which coöperates with the opposite edge of the applying roll from the supporting roll and the other being spaced from the companion portion and from the supporting roll. 30
8. In a cementing apparatus, a cement-applying roll, a lever fulcrumed below the roll, a work-supporting roll rotatable upon the lever opposite the edge of the applying roll, a support fixed to the lever and having two work-engaging portions, one of which coöperates with the opposite edge of the applying roll from the supporting roll and the other being spaced from the companion portion and from the supporting roll, and connections between the lever and support permitting the height of its work-engaging face to be varied. 40
9. In a cementing apparatus, cement-applying means, work-supporting means, and fold-preventing means coöperating with opposite sides of the work adjacent to the applying means. 50
10. In a cementing apparatus, cement-applying means, work-supporting means, and plural fold-preventing means coöperating with the work adjacent to the applying means, said fold-preventing means being mounted to move together to vary their contact with the work. 55
11. In a cementing apparatus, cement-applying means, work-supporting means, and a scraper contacting at its extremity only with the work adjacent the applying means. 60
12. In a cementing apparatus, cement-applying means, work-supporting means, and scrapers contacting with opposite sides of the work at one side of the applying means. 65
13. In a cementing apparatus, cement-applying means, work-supporting means, a work gage, and resilient members contacting with opposite sides of the work adjacent to the gage. 70
14. In a cementing apparatus, cement-applying means, work-supporting means, and a scraper situated at one side of the applying means and having its edge extending into engagement with the work in a direction substantially at right angles to the surface thereof. 80
15. In a cementing apparatus, cement-applying means, and opposite members inclined at an acute angle to one another and having adjacent ends bent to approach one another in substantially a straight line for contact with the work. 85
16. In a cementing apparatus, cement-applying means, work-supporting means, a work gage, and means mounted on the gage for engaging opposite sides of the work. 90
17. In a cementing apparatus, cement-applying means, work-supporting means, a work gage, projections from the work-engaging face of the gage, and opposite work-engaging members carried by the projections. 95
18. In a cementing apparatus, cement-applying means, work-supporting means, a work gage, studs mounted to turn on the work-engaging face of the gage, securing means for the studs, and coöperating resilient members carried by the studs. 100

In testimony whereof I have signed my name to this specification. 105

JOHN W. COSGROVE.
